US0D1076096S

(12) **United States Design Patent** (10) **Patent No.:** **US D1,076,096 S**
(45) **Date of Patent:** ** *May 20, 2025

(54) **RADIOGRAPHIC DETECTOR HOLDER**

(71) Applicants: **Maria Kathleen Brinck**, Cincinnati, OH (US); **Joseph Frank Clear, III**, Hamilton, OH (US); **Evan Joseph Johannigman**, Cincinnati, OH (US); **Josh Thomas Yokum**, Cincinnati, OH (US)

(72) Inventors: **Maria Kathleen Brinck**, Cincinnati, OH (US); **Joseph Frank Clear, III**, Hamilton, OH (US); **Evan Joseph Johannigman**, Cincinnati, OH (US); **Josh Thomas Yokum**, Cincinnati, OH (US)

(*) Notice: This patent is subject to a terminal disclaimer.

(**) Term: **15 Years**

(21) Appl. No.: **29/713,174**

(22) Filed: **Nov. 14, 2019**

(57) **CLAIM**

The ornamental design for a radiographic detector holder as shown and described.

DESCRIPTION

FIG. 1 is a right, top isometric view of a second embodiment of the radiographic detector holder shown in a closed state; FIG. 2 is a left, bottom isometric view thereof; FIG. 3 is a front elevation view thereof; FIG. 4 is a rear elevation view thereof; FIG. 5 is a right-side elevation view thereof; FIG. 6 is a cross-section view taken along line 6-6 of FIG. 3 thereof; FIG. 7 is a top plan view thereof; FIG. 8 is a bottom plan view thereof; FIG. 9 is a right, top isometric view shown in an open state; and, FIG. 10 is a top plan view of the view of FIG. 9. The broken lines in the drawing views depict features and environment of the radiographic detector holder that form no part of the claimed design.
